UNITED STATES PATENT OFFICE.

PAUL LOUIS CHAMONNOIS, OF VILLIERS-LE-SEC, CREUILLY, FRANCE.

MOTOR-PLOW.

1,391,366.

Specification of Letters Patent. Patented Sept. 20, 1921.

Application filed January 29, 1913, Serial No. 744,987. Renewed March 31, 1921. Serial No. 457,360.

(GRANTED UNDER THE PROVISIONS OF THE ACT OF MARCH 3, 1921, 41 STAT. L., 1313.)

To all whom it may concern:

Be it known that I, PAUL LOUIS CHAMONNOIS, a citizen of the French Republic, residing at Villiers-le-sec, Creuilly, Calvados, France, have invented certain new and useful Improvements in a Motor-Plow, (for which I have filed an application in France, Feb. 1, 1912, Patent # 479,793,) of which the following is a specification.

10 This invention relates to an automobile plow of that type in which a hauling rope is used for propelling the plow. The oscillating plow frame has shares at each end which throw out to the right and to the left.

15 The propelling of this plow is effected by means of a motor acting upon a rope anchored at convenient points and extending from one end of the field to the other. The plow is moved along this rope by means of 20 rope disks driven from the motor, the rope being wound around these disks. A steering apparatus acts upon the rope so that the furrow wheel can be always maintained in the furrow.

25 If a plow is operated by means of a hauling rope instead of by a chain (which is much more advantageous owing to the lesser weight of the rope) the difficulty is to obtain a sufficient adherence of the rope upon 30 the disks. This can be obtained only by a strong tension of the rope which must exist from one end of the field to the other up to the two points at which the hauling rope is anchored. With such a tension the steering 35 is possible only if the rope runs in and out at two points standing close together and situated in the median plane of the plow parallel with the direction of movement.

The invention relates to the special construction of the driving disks and of the 40 guide block which present all the advantages mentioned above.

In the accompanying drawings the invention is shown:

45 Figure 1 is a side elevation of the plow. Fig. 2 is a plan view of the fixed frame of the plow.

Figs. 3 and 4 are a side elevation and a plan view of the steering apparatus.

50 The automobile plow comprises a fixed frame 1 which always remains horizontal and upon which are mounted at the one side a furrow wheel 2 and at the other side two wheels 3 and 4, said wheels being adjustable

in vertical direction. Upon the frame 1 there are further mounted two disks 7 and 8, the motor 9 and the steering apparatus. A V-shaped oscillating frame 5 with shares 6 is pivotally mounted upon an axle 11 of the fixed frame 1.

The steering apparatus consists of a block 12 (Figs. 3 and 4) in which two vertical disks 13 and 14 are loosely mounted which are situated in the longitudinal plane. Two pairs of vertical drums 15, 16 and 17, 18 are further mounted in said block 12.

The block 12 forms a nut and is screwed upon two parallel screw spindles 19, 20 situated in the transverse plane and along which the block can move when said screw spindles 20 are being turned simultaneously. The hauling rope 21 for propelling the plow comes from the left, runs in under the disk 13, passes between the two pairs of drums 15—18 and 16—17, is wound three times 75 around the disk 7 beginning from above, leaves this disk beyond the center, passes again between the two pairs of drums 15—16 and 17—18, is wound three times around the disk 8 which it leaves above the 80 center, passes under the disk 14, between the two pairs of drums 15—18 and 16—17 and runs out toward the right to the other end of the field. The two hauling disks 7—8 are simultaneously driven from the 85 motor by means of a transmission, not shown, and they can be simultaneously thrown out of gear.

The steering of the plow is obtained by moving the block 12 upon the screw spindles 90 19—20, and the point of attachment of the rope 21 coming from the left being thus modified with regard to the plow, said plow is turned to the right or to the left.

The moving of the two screw spindles 95 19—20 can be effected by means of a hand-wheel, not shown. This hand wheel can be connected with the fixed frame 1, in which case it stands vertical and at the side of the furrow wheel 2 so that the driver 100 can easily ascertain whether the plow moves in proper direction. There could further be arranged two seats for the driver, one upon each of the arms of the V-shaped oscillating frame. In this case the shaft of 105 the hand wheel is articulated so that it can be used from both seats.

The rope disks with horizontal axle be-

ing situated under the frame the size of the device is reduced as much as possible and these parts do not interfere with the oscillating movements of the V-shaped frame.

The running in and out of the rope is effected in such a manner that the different sides of the rope are not in contact whereby wear of the rope is avoided.

10 This device permits without changing the rope, of moving forward or backward. The steering apparatus permits of maintaining the plow strictly in a determined direction at either the forward or backward movement.

Having thus described my invention what I claim is:—

A device for propelling and steering an automobile plow with hauling rope, having 20 a system of rope disks around which the

fixed rope is wound the plow being propelled along this rope which is guided by drums adapted to be displaced transversely characterized by the arrangement according to which the steering apparatus consists of a 25 block which forms a nut upon two horizontal transverse screw spindles, said block being adapted to be moved along said spindles, and having two vertical loose rope disks situated in a longitudinal plane and four 30 drums with vertical axles arranged between said horizontal rope disks under the fixed frame of the plow.

In witness whereof I have hereunto set my hand in the presence of two witnesses.

PAUL LOUIS CHAMONNOIS.
